UNITED STATES PATENT OFFICE.

GUY W. BLACKBURN, OF ELGIN, ILLINOIS, ASSIGNOR TO ELGIN SILVER PLATE COMPANY, OF ELGIN, ILLINOIS, A CORPORATION OF ILLINOIS.

COFFIN HANDLE.

1,402,041.

Specification of Letters Patent.

Patented Jan. 3, 1922.

Application filed October 16, 1919. Serial No. 331,036.

To all whom it may concern:

Be it known that I, GUY W. BLACKBURN, a citizen of the United States, residing at Elgin, in the county of Kane and State of Illinois, have invented a certain new and useful Improvement in Coffin Handles, of which the following is a specification.

My invention relates to improvements in steel coffin handles and in process of manufacturing the same.

It will be understood that a coffin handle always comprises an escutcheon plate which rests against the side wall of the coffin and which is ornamental in its nature, and a handle arm which is pivoted on the escutcheon plate and normally hangs down along the side wall of the coffin, but is free to rotate upwardly into a substantially horizontal position being there limited in its rotation by the escutcheon plate when the coffin is to be lifted by the handle.

Both these parts are in my preferred form, made of steel stampings and are separately finished and then assembled. When assembled they are fastened together by a relatively light and delicate hinge made up of integral lugs on one of the parts in rotatable engagement with perforations in the other but this hinge does not in my preferred form carry the load when the handle is used to raise the coffin, this load is carried by a fulcrum arrangement whereby the handle is engaged toward its inner end by an upwardly projecting lug on the escutcheon plate and at a point intermediate its ends, is engaged by the escutcheon plate itself so that the pivot connection serves only to prevent disengagement of the handle arm and the escutcheon plate but does not carry the load of the coffin when the handle is being used.

In my preferred form there are two short lugs projected inwardly from opposite sides of an aperture therein, the escutcheon plate of the handle arm has two parallel perforated ears bent inwardly toward one another, the end of the arm having these ears is thrust into the aperture in the escutcheon plate until the perforations are in register with the lugs. The operator then bends these perforated lugs outwardly to bring them into pivot engagement with the lugs on the escutcheon and the two parts are thus fastened pivotally together.

Among, the objects of my invention are to provide a new and improved form of steel coffin handle and escutcheon plate. Another object is to provide a cheap and durable coffin handle, another object is to provide convenient means for assembling the two parts of the steel coffin handle so that both parts may be separately finished before being joined together. Another object is to provide rigid and durable means to limit the relative rotation of both arm and escutcheon plate. Other objects will appear from time to time in this specification.

My invention is illustrated more or less diagrammatically in the accompanying drawings wherein:

Figure 1 is a plan view of the escutcheon;

Figure 2 is a section on the line 2—2 with the handle arm itself in place;

Figure 3 the section on the line 3—3 of Figure 1 showing the handle arm in place;

Figure 4 is a bottom plan view of handle arm and escutcheon plate showing the arrangement of the parts after assembly.

Figure 5 is a detail on a larger scale of a portion of the parts of Figure 4 showing the ears before assembly.

Like parts are indicated by like characters in all the drawings.

A is an escutcheon plate adapted to be fastened by means of screws A¹ on to a coffin A⁵, this plate is outwardly bulged as shown in Figure 2 and apertured as at A², A³ is a lug extending upwardly from the bottom wall of the aperture A² substantially parallel with the wall of the coffin and its upper end therefore is about $\frac{1}{2}$ inch inwardly from the upper boundary of the aperture A² because that aperture is made in the convex escutcheon plate. A⁴ A⁴ are pivot lugs extending inwardly from the two side walls of the aperture A² a short distance toward the lug A³. It will be understood that this escutcheon plate with the lugs is made as a single integral steel or other metal stamping.

B is a handle arm, it terminates in an outwardly extended loop B¹ adapted to engage the handle bar B² the loop is closed upon the horizontal arm by means of the bent ears B³ engaging slots in the under inward end of the loop. B⁴ B⁴ are ears projecting from and integral with the side walls of the handle. They are perforated at B⁵ and

before assembly with the escutcheon plate are bent inwardly as shown in Figure 5.

The device is assembled by pushing the end of the handle bar into the perforation 5 in the escutcheon until the small lugs on opposed walls of the perforation therein are in register with the perforations in the ears then a tool is inserted between the perforated ears and they are spread until they are substantially in parallelism thus engaging the 10 pivot lugs on the plate and fastening the parts together in pivotal relation, as shown in Figure 4.

Attention is called to the inner end of the 15 handle arm which is bent downwardly on an arm substantially concentric with the perforations in the ears so that the lug A³ comes into operative end engagement with the handle arm almost as soon as rotation 20 commences. Attention is also called to the groove C in the upper surface of the handle adapted to engage the edge of the wall of the escutcheon plate where it is apertured or perforated and thus position the parts 25 thus relieving the pivot lugs of any part's strain owing to lateral displacement of the parts.

It will be evident that while I have shown 30 in the drawing an operating device still many changes might be made both in size, shape and assembling parts, their position and operation might be radically changed, material other than steel might be used; the 35 position of both lugs and both ears might be changed and might be reversed and placed upon other parts of the assembly and many other changes might be made without departing materially from the spirit of my invention, and I wish therefore to put my 40 drawing as in a sense diagrammatical.

The handle arm at its end is downwardly curved where it engages the end of the lug or abutment so that when a load is on the handle, there will be no possible chance of 45 the handle being pulled out away from the escutcheon plate as might be the case where friction alone were relied upon to hold the handle arm against lateral displacement, the idea being that with the end of the arm downwardly curved as indicated, the handle arm cannot be withdrawn quite independent of the pivot connection without the downward rotation which obviously is impossible when there is a load on the handle. This 55 curved surface thus tends to cause the handle arm to move longitudinally inward and in order to prevent binding, that tendency is limited and resisted by the engagement of the curve in the handle arm with the edge of the escutcheon plate.

The use and operation, of my invention are as follows:

Commencing first with the process of manufacture, the escutcheon plate is normally stamped out of a single flat steel or

other metal blank, so as to give it its convex contour, its ornamentation, and the aperture or perforation which is penetrated by the end of the handle arm. This escutcheon plate after being stamped out, is finished by 70 itself. The handle arm is also stamped from a single piece of metal and separately finished with its two pivot ears bent together so that the distance between them is less than the distance between the two short 75 lugs on opposed sides of the perforation in the escutcheon plate. After the two parts have been completely finished, they are assembled by inserting that end of the handle arm which has the ears, into the aperture 80 in the escutcheon plate until the ears are in register with the opposed lugs. The ears then bend apart until substantially parallel at which time, the lugs penetrate the perforations in the ears and provide a pivot connection between the escutcheon plate and the handle arms.

This pivot connection is, of course, not a strong enough one to carry the weight of the coffin when the handle is used for that 90 purpose, for this weight is carried by the engagement of the handle arm adjacent its outer end on its side with the fulcrum lug in the aperture in the plate and its engagement intermediate its end on its upper surface with the edge of the plate where it is apertured. This arrangement completely limits the upward rotary excursion of the handle arm with respect to the escutcheon 95 plate, but it is necessary to go even farther than this and make it impossible to withdraw the arm without rotating it, thus avoiding the possibility of the operator pulling the arm out while lifting the handle.

This last requirement is effected by curving the end of the handle downwardly so that when in the upper working position, the extreme outer end of the handle is lower than the top of the fulcrum lugs, thus the only way in which the handle arm can be 110 withdrawn is by rotating downwardly until the end is raised above the fulcrum lugs. This, of course, cannot take place while any weight is being carried.

Incidentally this curvature of the extreme 115 end of the handle has an aesthetic value because when the handle is hanging down in its inoperative position, the curved end just comes flush with the escutcheon plate, and so no unsightly gap is left.

The clutch or notch in the upper surface of the handle arm co-operates with the curved end of the arm by engaging the edge of the escutcheon plate to insure that there will be no lateral movement of the arm and 125 thus the relatively weak pivot connections will be protected.

I claim:—

1. A coffin handle comprising an escutcheon plate having two spaced abutment parts, 130

a handle arm pivoted thereon and arranged to engage said abutment members when in the operative position and to have its rotation limited by such engagement, one of 5 said abutment parts comprising a lug upwardly extending to engage the under side of the handle arm, the bearing surface of said lug lying in the same horizontal plane as that of the other abutment part.

10 2. As a new article of manufacture a coffin handle comprising an escutcheon plate, a handle arm pivoted thereon, a lug adapted to engage the under side of the arm, an abutment part adapted to engage the upper 15 per side of the handle arm to limit its rotation, the bearing faces of the lug and the abutment parts lying substantially in the same horizontal plane, the end of the handle arm being downwardly curved where it 20 engages the lug, the upper surface of the

handle arm being grooved where it engages the abutment.

3. A coffin handle comprising an escutcheon plate having two spaced abutment parts, an open bottomed handle arm pivoted thereon and arranged to engage said abutment member when in the operative position and to have its rotation limited by such engagement, one of said abutment parts comprising a lug upwardly extending and penetrating into the interior of the handle arm, to engage the lower surface of the top of 25 30 said handle arm.

In testimony whereof, I affix my signature in the presence of two witnesses this 26th 35 day of September, 1919.

GUY W. BLACKBURN.
